CLAIM

The ornamental design for forward part of a pair of jaws for folding pliers, as shown and described.

DESCRIPTION

FIG. 1 is an isometric view from the upper left rear of a forward part of a pair of jaws for folding pliers showing my new design, wherein the broken line depictions of a rearward part of the jaws and of a pair of pliers handles are shown for illustrative purposes and form no part of the claimed design;

FIG. 2 is a top plan view of the forward part of a pair of jaws for folding pliers shown in FIG. 1, the bottom plan view thereof being identical therewith;

FIG. 3 is a left side elevational view thereof, the right side view being identical therewith;

FIG. 4 is a front, or jaw tip, end elevational view thereof; and,

FIG. 5 is a rear end elevational view thereof.
